FREE-PLAY DEVICE

Myer Gensburg, Chicago, Ill., assignor to Genco, Inc., Chicago, Ill., a corporation of Illinois

Application November 14, 1938, Serial No. 240,321

13 Claims. (Cl. 273—119)

This invention relates to repeat-operating mechanism particularly useful in coin-controlled devices and coin-operated game and amusement apparatus, and sometimes referred to as a free-play control, the principal object being the provision of an improved device of this class which is simple and inexpensive in construction, reliable in operation and of general application.

More particularly stated, it is an object of the invention to provide a variable stroke operating device including a slide bar arranged to move back and forth, and a shiftable controlled member engaged and actuated by movable interconnecting means on the slide bar when the latter is moved a predetermined distance toward the controlled member, the interconnecting means being movable out of its normal position into alignment with an advance portion on the controlled member with the result that the slide bar may engage the controlled member by movement less than said predetermined distance, the slide bar preferably being reciprocated through the agency of a coin-controlled slide which is capable of movement to move the slide bar the necessary predetermined distance only when a coin is deposited in the coin slide, the latter otherwise having only a limited idle stroke movement which, however, is sufficient to move the slide bar provided the interconnecting free-play member is moved to shorten the stroke or distance necessary for the slide bar to be moved to actuate the controlled member.

It is a further object to provide actuating means, preferably in the form of an electromagnet, movable with the slide bar for effecting movement of the free-play member into effective position.

It is another object to arrange the free-play mechanism in combination with game apparatus having a coin control so that a predetermined score or objective must be attained in the game in order to actuate the free-play device and shorten the stroke necessary for the actuating member or slide bar to move to release the game for another free-play without deposit of a coin in the coin slide.

It will be understood that the invention in its broader aspects may be embodied in arrangements other than that specifically described hereinafter for purposes of illustration in view of the preferred construction shown in the drawings.

Other objects and advantages of the invention will appear as the following description proceeds in view of the drawings, in which:

55. Fig. 1 is a fragmentary vertical section through

a bagatelle game employing the free-play mechanism;

Fig. 2 is a fragmentary bottom plan view of the playing field, showing the free-play mechanism as viewed in the direction of line 2—2 of Fig. 1; 5

Fig. 3 is a fragmentary bottom perspective of the playing board, the free-play mechanism, and the game-actuated control switches;

Fig. 4 is a fragmentary vertical section, to reduced scale, showing the ball elevating means; 10

while

Fig. 5 is a circuit diagram.

In the preferred arrangement, the free-play mechanism is incorporated in an amusement device including a cabinet 10 (Fig. 1) having a 15 horizontally inclined ball playing board 11 therein, and in which board are a plurality of ball pockets or openings 12 (Fig. 2 also) and into which balls gravitating over the playboard may fall to rest upon control members in the form 20 of ball-operated switches 13.

The switches 13 are variously mounted on straps 14 which are secured to crossbars 15 (Fig. 3), the crossbars in turn being rigidly secured to parallel slide bars 16 which, together with the 25 several crossbars, comprise a framework which constitutes a shiftable or reciprocably sliding controlled instrumentality or mechanism which it is an object of the invention to actuate through the agency of the novel free-play mechanism 30 hereinafter to be described. The parallel slide bars 16 of the shiftable switch-bearing frame structure are secured in cleats 17 on the under side of the playboard and are thus mounted for sliding or shifting reciprocation to move the 35 switches 13 into and out of ball obstructing position beneath the corresponding ball exits 12, there being a spring 18 attached to the switch-bearing frame structure to urge the latter (toward the left, Figs. 2 and 3) into a normal position with the several switches 13 disposed beneath their respective ball openings so that should a ball enter one of the latter, the corresponding switch will be operated for purposes hereinafter described. 40

The controlled member or switch-bearing frame 15—16 is adapted to be shifted into ball releasing position by operation of a master control or coin slide so that any pocketed balls will be released to fall upon an inclined apron 19 50 (Fig. 4) for delivery into position to be elevated by an elevator 20 actuated by a plunger 21 whereby the balls are positioned one by one in front of a ball projecting plunger 22 which may be manipulated by the player to propel balls onto 55

the upper end of the playboard for movement over the latter into one or another of the pockets 12.

Means for shifting the controlled member or switch-bearing frame (also commonly referred to as a shuffle panel in some of its forms), includes the arrangement of a master control in the form of a coin slide 25 mounted on a front wall of the cabinet 10 opposite the lower end of the playboard and including a reciprocable operating slide 26, the inner end of which is disposed, when the slide is pushed inwardly a predetermined distance (upon deposit of a coin therein), to engage the offset or depending arm 28 of a reciprocable actuating slide bar 29 which is slidably mounted at one end in the cleat 17 along with the frame bar 16, but which at its opposite (left-hand) end is provided with a rigid T bar 30 having parallel legs 31 at its extremities and which are mounted in cleats 32 to slide in a direction parallel with the main bar 29. The rear or right-hand end of the slide bar 29 is upset as at 33 for rigid connection with a brace or truss 34 which is secured at its opposite end to the depending arm 28 to reinforce the latter, it being observed in Fig. 1 that the brace 34 is disposed at an appreciable distance below the slide bar 29 (or above bar 29 in Fig. 3).

Means providing a thrust contact on the "shuffle panel" or controlled frame structure, includes an arm 35 which is spot welded or otherwise secured as at 36 to one of the arms 46 on the switch-bearing frame, and which has an upset end flange 37 constituting a thrust receiving contact surface against which means on the slide bar bears when the bar is moved inwardly a predetermined distance, it being observed also that the arm 35 lies above the slide bar 29 alongside the upturned contact end 38 of the frame bar 16, attention being called to the fact that the end portion 38 lies in advance of the upset flange 37 in a direction toward the left and hence toward the master control or slide 26.

In the normal operation of the game, the player deposits a coin in the master control and moves the slide 26 inwardly, the coin freeing the latter for a full stroke movement so that the inner end of the slide 26 will bear against the depending arm 28 on the actuating slide 29, with the result that the latter will likewise be moved inwardly (toward the right).

Means for establishing an operative connection between the actuating slide bar 29 and the controlled slidable member or "shuffle panel" 15-16, includes the provision of an arm 40 pivotally mounted as at 41 on the actuating slide bar 29 and provided with an upset free end portion 42 adapted to bear against the thrust flange 37 when the actuating slide has been moved a predetermined distance inwardly or toward the right by operation of the master control 26 in the manner aforesaid, whereupon continued movement of the slide bar in this same direction will shift the members 16 to withdraw the switches 12 from blocking position beneath the ball exits, thereby freeing a predetermined number of balls for elevation and projection by the player by the means previously described. It may be observed that the coupling means or arm 40 is disposed in the normal position shown in Fig. 3 by means constituting a part of the free-play mechanism, as will hereinafter appear.

As balls are projected out onto the field by the player, they will become lodged in various pockets 12 and actuate the corresponding switches, which

in turn are arranged to control some desired form of signal or score indicating means, and in the event that the player is successful in lodging balls in certain pockets, the arrangement is such that he will be awarded one or more free plays, that is, one or more operations of the master control 26, without the necessity of depositing another coin in the latter. The mechanism for conditioning the game apparatus for repeat operation or a free play as aforesaid, includes the provision of means for moving the coupling member 40 out of its normal position (Fig. 3) (wherein it may engage the farther thrust flange 37), into a position where it will engage the nearer upset end portion 38 on the bar 16 whereby the actuating slide bar 29 must of necessity be moved a shorter distance before establishing operative engagement with the controlled member or "shuffle panel," so that it is not necessary to slide the bar 29 the whole of the aforesaid predetermined distance in order to effect release of the balls, the arrangement further being such that this foreshortened operating stroke of the slide bar 29 is equivalent to the idle stroke movement of the master control slide 26, with the result that the slide 26 may be moved the limited amount of which it is inherently capable, without deposit of a coin, to slide the bar 29 and the shiftable or control means 15-16 to effect release of the balls.

Means for actuating the coupling means 40 is preferably mounted on the slide bar 29 for movement with the latter, and this means in the preferred embodiment includes an electromagnet 45 suitably mounted on a plate 46, secured as by spot welding, to the end of the slide bar 29 adjacent the arm 28 thereof. A finger 47 is attached to the armature 48 of the magnet at one of its ends and has its opposite end projected into a slot 49 in a bracket 50 secured to the coupling arm 40, and due to the action of the spring 51 of the magnet armature, and the finger 47, the coupling arm 40 is urged into its normal position seen in Fig. 3, so as to dispose the upturned end portion 42 of the arm 40 out of the path of the upturned end 38 on the "shuffle panel," with the result that it is necessary that the slide bar 29 be moved the full predetermined distance inwardly in order to establish operative connection (by engagement of the parts 42 and 37) in order to actuate the controlled member or "shuffle panel."

The operating means or magnet 45 for the free-play mechanism is desirably arranged in a control circuit, such as shown in Fig. 5, wherein the operating means or electromagnet 45 is connected by a conductor 60 to one terminal 61 of the secondary of a transformer or other suitable power source, the remaining terminal of the magnet 45 being connected by conductor 62 to the movable contact 63 of a relay having a stationary contact 64 connected by a conductor 65 to the return terminal 66 of the transformer secondary. In the illustrative arrangement, the relay winding 61 has one of its terminals connected by a conductor 68 to a contact 13a on one of the ball switches, the companion contact 13b being connected to another ball switch contact 13c having a companion contact 13d connected by conductor 69 to the terminal 66 of the power source. The remaining terminal of the relay winding 67 is connected by a conductor 70 through a time-delay switch 71 and return conductor 72 to the opposite terminal 61 of the power source. Thus, in the illustrative arrangement, the relay 67 is controlled through a series arrangement of ball switches and also through a time-delay switch, 75

The operation of the free-play or repeat-operating mechanism is such that when balls become lodged in certain pockets overlying the switch contacts 13a and 13c, relay 67 will be energized through the time-delay switch 71 to pull up the movable contact 63 and energize the magnet 45 and pull up the armature 48 of the latter, whereupon the arm 47 will be moved to pivot the coupling arm 40 and dispose the upturned end 10 portion 42 thereof out of alignment with the thrust flange 37 and over in a position to engage the upturned end 38 which is disposed in advance of the flange 37, it being observed that in the present arrangement the magnet 45 remains energized so long as the switches 13a and 13c remain operated. The player may be apprised of the fact that he is entitled to a free game award by suitable signal mechanism operatively controlled through the switches 13a and 13c (not shown herein) or the particular ball pockets corresponding to the switches 13a and 13c may be designated appropriately on the playfield as constituting a skill award combination. The player being thus apprised of the fact that he is entitled to a free play, will push the master control slide 26 inwardly, the latter, however, being movable less than its usual stroke due to the fact that no coin needs be deposited therein, and the actuating control or slide bar 29 which is moved by the coin slide will be obliged to travel less than its predetermined full stroke in order to establish operative connection or coupling with the controlled or shiftable frame arrangement 15-16, such coupling being effected through the engagement of the upturned end 42 with the bracket end 38, which is disposed in advance of the thrust flange 37 in the direction of movement of the operating slide 29.

It will be apparent that the objects of the invention may be satisfactorily accomplished in the preferred arrangement described, which arrangement includes, broadly, the provision of a reciprocable actuating member arranged for movement a predetermined distance into operative engagement with a controlled member for actuation of the latter, and means for permitting actuation of the controlled member by movement of the actuating slide less than said predetermined distance, said means including a coupling device or interconnecting means movably mounted on the actuating slide and normally disposed in alignment for engagement with the controlled member when the actuating slide is moved the entire predetermined distance aforesaid, together with means for moving the coupling member out of alignment into position to engage a portion of the controlled member which is disposed in advance of the part thereof which is normally engaged by the coupling member when the latter is in aligned position, whereby the actuating slide bar need be moved only a part of its predetermined normal stroke to establish operative connection with the controlled member.

The invention is defined in the appended claims which are intended to include all equivalent arrangements and constructions with respect to the form, location, or operation of the claimed arrangement.

Having thus described my invention, what I claim as new and desire to protect by Letters Patent is:

1. In a device of the class described, variable stroke operating means including a reciprocable slide and a co-directionally reciprocable con-

trolled member adapted to be actuated by the slide and having a plurality of thrust-receiving members offset one behind another relative to the line of reciprocation of said slide, a movable interconnecting member carried with said slide and movable into position for engagement with one of said thrust members when the slide is moved toward the controlled member, the distance which said slide must be moved to effect operation of the controlled member depending upon whether said interconnecting member is positioned to engage a nearer or farther one of the thrust-receiving members, together with means for positioning said interconnecting member with respect to said thrust-receiving points. 15

2. In a device of the class described, including a controlled member, a variable stroke operating device comprising an actuating member arranged for back and forth movement relative to said controlled member, movable interconnecting means carried with said actuating member and arranged for movement into different positions relative to the actuating member to operatively engage the controlled member at points thereon which are relatively in advance or behind each other in the direction of movement of the actuating member, whereby the latter must make a longer or shorter stroke, depending upon the position of said movable interconnecting means, in order to operatively engage said controlled member, and means for moving the interconnecting means for the purpose aforesaid. 25

3. In a device of the class described, variable stroke operating mechanism including a mutually reciprocable actuating member and a controlled device, said controlled device having means providing thrust-receiving parts which are positioned one behind another in the direction of reciprocation of the actuating member, a pivoted interconnecting member mounted on said actuating member and arranged to be moved into alignment with one or another of said thrust-receiving parts to engage the same when the actuating member is moved toward the controlled device, said actuating member being moved different distances to effect operative engagement with the controlled device as aforesaid, depending upon whether the interconnecting member is positioned to engage a nearer or farther one of said thrust-receiving parts, and means including electromagnetic means mounted for movement with said actuating member and arranged to move and position said interconnecting member for the purpose aforesaid. 35 40 45 50

4. In a device of the class described, a variable stroke operating device including a reciprocable slide, a thrust arm pivotally mounted on said slide, and coacting spring and electromagnetic means for moving said thrust arm into different positions to engage thrust-receiving means, and a cooperating member arranged for actuation by said slide and having thrust-receiving means in different proximate and remote positions, thereon relative to said slide, for engagement by said thrust arm to actuate the cooperating member when said slide is moved toward the same. 55 60 65

5. In combination, a variable stroke operating slide having a thrust arm pivoted thereon, a controlled member arranged to move in the same direction as said slide and having offset thrust-receiving parts at least one of which lies farther from said slide than another in the direction of movement of the slide, and means for moving said thrust arm into various positions of alignment with one or another of said thrust-receiving parts. 70 75

ing parts to operatively engage the same upon movement of the slide toward said controlled member, the distance which said slide has to move depending upon whether the thrust arm 5 is positioned to engage a nearer or farther one of said thrust-receiving parts.

6. In combination, mutually reciprocable actuating and controlled members, a thrust member mounted on said actuating member for movement into various positions in a direction substantially transverse of the movement of the aforesaid members, and thrust-receiving means on said controlled member and offset from the line of said direction of movement of the controlled member and one of the same lying farther away from said thrust arm than the other in said direction, and means for moving said thrust arm into position to engage a desired one of said thrust-receiving means to vary the distance which it will be necessary to move the actuating member from an initial position toward the controlled member to operatively engage the latter.

7. In combination, a mutually reciprocable slide and shiftable member, the latter having thrust-receiving portions stepped away from said slide in the direction of movement thereof, and variable stroke means including a pivoted thrust arm on said slide and coacting spring and electro-magnetic means mounted for movement with the slide and arranged for operation to move said thrust arm into alignment with a desired thrust-receiving portion for operative engagement with the same when said slide is moved from an initial 30 position toward said shiftable member, the distance which said slide must be moved to effect operative engagement with the shiftable member depending upon whether said thrust arm is positioned in alignment with a nearer or farther thrust-receiving portion.

8. In combination, an actuating member arranged for back and forth movement, movable interconnecting means carried with said actuating member, spring means urging said interconnecting means into a normal position, a shiftable member arranged in the path of said interconnecting means for engagement and movement by the latter in its aforesaid normal position when the actuating member is moved a certain distance 45 from a normal position toward said shiftable member, and means mounted for movement with said actuating member and operable to move said interconnecting means from said normal position thereof into a different position such that 50 said actuating member must be moved a distance different from the aforesaid certain distance in order to operatively engage said shiftable member.

9. Control mechanism including a controlled member provided with an engaging part disposed in advance of a second engaging part, an actuating member adapted for cooperation with an operating control and arranged for reciprocation relative to said engaging parts, coupling 60 means movably mounted on said actuating member and normally disposed in alignment to engage the farthest one of said engaging parts so that the actuating member must normally be moved a predetermined distance in order to engage and operate the controlled member, said coupling means being movable out of said normal position to be engageable with said second and nearer engaging part whereby the actuating member 65 may be moved less than said predetermined distance to operate the controlled member, and means for moving the coupling means into and out of said normal position.

10. Operating means including an actuating member arranged for back and forth motion, a movable coupling element on said actuating member, and a controlled device arranged to be engaged and operated by said coupling element when said actuating member is moved a predetermined distance toward the controlled device from an initial position with said coupling element disposed in a normal position, said coupling element being movable out of said normal position for engagement with the controlled device for operation of the latter by a movement of the actuating member less than said predetermined distance, and means for moving the coupling member into and out of normal position as aforesaid.

11. Operating mechanism including a controlled device having offset thrust-engaging parts, an actuating member arranged for back and forth movement relative to said thrust-engaging parts, one of the latter being farther than the other from said actuating member in the direction of back and forth movement, a movable coupling member mounted on said actuating member for back and forth movement into and out of alignment with one or the other of said thrust-engaging parts so that said actuating member must be moved a predetermined distance to effect operative engagement with said controlled member, said actuating member being moved less than said predetermined distance to effect operative engagement as aforesaid when the coupling member is positioned to engage the nearer thrust-engaging part, and means for moving said coupling member back and forth relative to the thrust-engaging parts as aforesaid.

12. In a device of the class described, a reciprocable actuating member arranged for movement from a normal position a predetermined distance to operate a controlled device, movable interconnecting means arranged for movement with said actuating member and operable when in a normal position to operatively engage said controlled device when the actuating member is moved said predetermined distance whereby to actuate the controlled device, said interconnecting means being movable from its normal position aforesaid into position to operatively engage the controlled device when said actuating member is moved a certain amount less than said predetermined distance, and means for effecting movement of said interconnecting means into and out of normal position for the purpose aforesaid.

13. In a device of the class characterized, an actuating member arranged for movement from a normal position a normal predetermined distance to engage a controlled member for operation of the latter, and means including a movable member arranged for cooperation with said actuating member for movement from a normal position, relative to said actuating member, into a position for operative engagement with said controlled member, said actuating member being moved less than said predetermined distance in order to effect the aforesaid operative engagement of the movable member whereby the latter may be operated by movement of the actuating member less than the normal predetermined distance, and means for moving the movable member into and out of normal position as aforesaid.
